IRONING MACHINE

Peter Eduard Geldhof, Syracuse, N. Y., assignor to
 Easy Washing Machine Corporation, Syracuse,
 N. Y., a corporation of Delaware

Application November 27, 1933, Serial No. 699,936

26 Claims. (Cl. 38—61)

My invention relates to ironing machines and more particularly to a novel combined table and cover therefor, and is a continuation in part of my co-pending application, Serial No. 662,511, filed March 24, 1933.

An object of my invention is to provide a supporting stand and cover for an ironing machine which, when the ironing machine is not in use, may be utilized as a table.

Another object of my invention is to provide a cover for an ironing machine which, when it is desired to use the ironing machine as such, may be easily rotated from a position covering the ironing elements to a position to permit free access thereto.

My invention further contemplates the provision of a cover for an ironing machine which may, by a simple linkage, be manually rotated from a position covering the ironing elements to a position alongside the ironing stand and below the ironing elements.

A further object of my invention is to provide means for permitting manual movement of an ironing machine cover from a position enclosing the ironing elements to a position such as to permit free access thereto and in addition provide a spring associated with said means for initially decreasing the manual effort required to move the cover, said spring serving, when the cover approaches a position alongside the ironing stand, to restrain the movement of the cover whereby the cover is prevented from striking the ironing stand with any great degree of force.

My invention further contemplates the provision of means whereby the cover may, with little manual effort, be swung from a position covering the ironing elements, released part way in its movement, and permitted to swing and ease into position alongside the ironing stand without bumping heavily thereagainst.

Other objects and advantages of my invention will be more apparent from the following description, taken in connection with the accompanying drawings, in which:

Figure 1 is a view taken on line 1—1 of Figure 2 showing the position of the cover enclosing the ironing elements and in dotted lines, the position of the cover when the ironing elements are exposed.

Figure 2 is a view taken on line 2—2, Figure 1, in the direction indicated by the arrows.

Figure 3 is a view taken on line 3—3 of Figure 1.

Figure 4 is a view taken on the line 4—4 of Figure 1.

Figure 5 is a view taken on the line 5—5, Figure 1.

Figure 6 is a view taken on line 6—6, Figure 1.

Figure 7 is a view taken on line 7—7, Figure 1.

Figure 8 is a view taken on line 8—8 of Figure 2.

Figure 9 is a cross-section on line 9—9, Figure 4.

My invention, in general, comprises an ironing stand 11, supported by legs 12 on which is mounted, as indicated in dotted lines, an ironing machine comprising the usual ironing roll 13, ironing shoe elements 14, and controls 16. Enclosing the ironing elements, I have provided a cover 17, the top of which, as the surface 18, may be employed when the ironing machine is not in use as such, as a table. The side-walls of the cover are preferably bent at 15 and rebent to form a depending ledge and the table surface has a depending lip 19 adapted to fit over and be secured in position on the rebent portion of the side-walls. Thus the complete assembly may be utilized in a kitchen as a table, has a utility separate and apart from its use purely as an ironing machine and, therefore, need not be stored after the ironing operations have been completed.

The cover 17 is supported in position on the ironing stand 11 and is movable on a pair of links 21 which are pivoted to the ironing stand 11 on opposite sides thereof through a pivot rod 22. The pivot rod 22 is secured and rotatable in a pair of brackets 23 which are riveted or otherwise suitably secured to the ironing stand 11. The rotatable rod 22 or equalizing bar and 30 the links 21 secured thereon move as a unit with respect to the table and in shifting the cover from a closed position to an open position and vice versa, and act to retain the sides of the cover in the same relative position during such 35 movement. The connection between the link 21 and the equalizing bar 22 may be produced in any suitable way for effecting their simultaneous rocking movement, and as shown herein, the end of the equalizing bar 22 is flattened as shown at 40 71 on opposite sides and the link 21 is formed with an elongated slot which fits tightly over the flattened portion of the bar 22 and is secured thereon in any suitable way as by upstanding 45 the head of the bar against a washer 10. If desired, the links may be pivotally secured directly to the ironing stand and the bar rigidly secured to the arms at any convenient position along the length of the links.

Each of the pivot arms is preferably bent at its 50 upper and lower extremity, the lower bent portion of each of the links lying substantially parallel to the top of the ironing stand when the cover is in a closed position and the upper bent portions at their extremities being pivoted as at 28 to 55 the cover preferably above the center line thereof.

Although the pivot action between the cover and the links may be accomplished in any suitable manner, a housing 27 is preferably welded 60

or otherwise secured to each side of the cover 17 in each of which is rotatably mounted a pivot member 28. The pivot member extends through an aperture formed in the housing 27 and passes through an aperture formed in the links 21, a cotter pin 29 or other suitable means being utilized to retain the links on the pivot member 28. A pair of coiled springs 31 are mounted internally of the cover. An end coil 32 of each of the springs is secured in an aperture formed in the extremity of the straight portion of each of the links 21 and the opposite ends are secured in brackets 33 welded or otherwise secured in the upper corners of the cover.

15 A second pair of links 34 are positioned on opposite sides of the ironing stand, one end of each of which is pivotally secured as at 36 to the cover. The other end of each of the links 34 is pivotally secured as at 37 to the legs of the ironing stand. The pivot action between the cover and the links 34, as shown in Figure 4, is accomplished by means of projecting arms 38 which are secured by rivets 39 to a bar 41 welded to the inside of the cover as at 42. The bar extends completely around the internal lower wall of the cover and serves to reinforce and prevent the lower edges of the cover from being deformed. The bar 41 is bent inwardly at 44 to accommodate the projecting arms 38 between the inside of the cover and the bar 41, the cover being apertured to receive the arms 38.

The outer portions of each of the projecting arms 38 is decreased in diameter to rotatably receive the links 34 which are secured in position by snap rings 47. The other end of each of the links 34 is secured to pivot members 48 by means of snap rings 49, the pivot members 48 being retained on the legs 12 of the ironing stand by means of retaining nuts 51. It will be noted that the pivot arms 21 are located internally of the cover 17, while the links 34 are located externally thereof. Preferably the links 21 and 34 are so positioned and proportioned with respect to each other that when the cover reaches its final position, it lies vertical, with its upper edge in close proximity to the legs of the ironing stand.

To prevent the cover, when it is moved to a position enclosing the ironing elements, from marring the ironing stand 11, a pair of bumpers 54 are provided which are secured to the forward corners of the inside wall of the cover 17. The bumpers, more clearly shown in Figure 8, comprise U-shaped pieces of rubber or other suitable material which straddle the bar 41 and extend slightly below the plane of the lower edge of the cover. The bar 41 is bent outwardly from the internal side walls of the cover to accommodate the bumpers 54, the bumpers being retained in position by means of bolts 56. The bumpers 54 contact with reinforcing flanges 61 secured as by welding to a depending portion 62 of the top of the supporting stand 11. The depending portion serves as an apron around the stand, the legs 12 being removably screwed in position on the internal wall of the apron.

In moving the cover from the position shown in solid lines in Figure 1 to the position shown in dotted lines, the cover 17 is lifted and rotated bodily about the pivot rod 22 as a center to the position shown in dotted lines where the bottom edge of the cover rests against bumpers 69. The bumpers 69 are preferably made of rubber and are retained in apertures formed in each of the rear legs 12 as shown in Figure 6. The links 34 move from a position substantially extending up-

wardly from the pivot points 37 to a position approximately 180 degrees away and prevent the cover from being rocked about the pivot points 26.

In moving the cover from the solid line position to the dotted line position the spring 31, when the cover is initially raised, is contracted. The spring thus exerts a force on the cover which decreases the initial manual effort required to rotate the cover. After a certain point in the movement of the cover is reached, the point 32 moves away from the bracket 33 in which the spring is retained. The spring is thus expanded and exerts a restraining influence on the movement of the cover whereby the cover is eased into the dotted line position without striking the bumpers 69 with too great a force. It will thus be apparent that the cover may be raised with little effort from a position enclosing the ironing elements, released partway in the movement, and allowed to swing and ease into the dotted line position without striking too heavily against the bumpers. Also it will be observed that when the cover is brought from the dotted line position to the solid line position in Figure 1, the cover may be raised with little effort because the spring 31 tends to aid the lifting movement, and further, when the cover approaches the position enclosing the ironing elements, the spring is again stretched so as to lower the cover gently into position without striking too heavily on the reinforcing angle member 61.

Although I have shown and particularly described the preferred embodiment of this invention, I do not desire to be limited to the exact construction shown, as various changes in the form and relation of the parts thereof may readily be made without departing from the spirit of this invention as set forth in the appended claims.

I claim:

1. In an ironing machine, an ironing stand including supporting legs and a surface supporting ironing elements, a cover enclosing the ironing elements resting on the ironing stand and adapted in such position to form with the ironing stand a table, a pair of links pivotally secured to the ironing stand and to the cover, a second pair of links pivotally secured to the ironing stand and to the cover, a rotatable bar extending between and secured to one of said pairs of links and serving, during movement of the cover on said links from a position enclosing the ironing elements to a position exposing the same, to cause the links to move together, and spring means connected to one of the pairs of links and to the cover in a manner and position such that said spring means is initially contracted and subsequently expanded during movement of said cover from one extreme position to the other so as to lessen the effort required to either open or close the cover.

2. In an ironing machine, an ironing stand including supporting legs and a fixed horizontal surface supporting ironing elements which project an appreciable distance above the level of the horizontal surface, a hollow box-like cover supported by the ironing stand and extending over and enclosing the ironing elements and forming with the ironing stand a table, a pair of links pivotally secured to the cover and to the ironing stand, cover guiding means secured to the cover and to the ironing stand, said links and cover guiding means determining the arc of movement of the cover as it is moved from a position en-

closing the ironing elements to a position exposing the same, a rotatable bar extending between and secured to said links, said links being so positioned as to enable the cover to swing so 5 that in its final position it extends vertically in close proximity to the rear legs of the ironing stand and with the front of the cover forming a substantially horizontal surface lying below the top level of the ironing elements.

10 3. In an ironing machine, an ironing stand including supporting legs and a fixed, horizontal surface supporting ironing elements which project an appreciable distance above the level of the horizontal surface, a hollow box-like cover supported by the ironing stand and extending over and enclosing the ironing elements and forming with the ironing stand a table, a pair of links pivotally secured to the cover and to the ironing stand, a second pair of links pivotally secured to 15 the cover and to the ironing stand, a rotatable bar extending between and rigidly secured to one of said pairs of links, said pairs of links and bar being so positioned as to enable the cover to be manually moved upwardly over the ironing elements 20 in a fixed predetermined arc to a substantially vertical position at the rear of the ironing stand in close proximity thereto and with the front of the cover forming a substantially horizontal surface of substantial width lying below the top level of the ironing elements.

25 4. In an ironing machine, an ironing stand including supporting legs and a fixed horizontal surface supporting ironing elements which project an appreciable distance above the level of the horizontal surface, a hollow box-like cover supported by the ironing stand and extending over and enclosing the ironing elements and forming with the ironing stand a table, a pair of links pivotally secured to the ironing stand 30 and to the cover, a second pair of links pivotally secured to the ironing stand and to the cover, a rotatable bar extending between and rigidly secured to one of said pairs of links, said pairs of links and bar being so positioned as to enable 35 the cover to be moved manually upwardly and over the ironing elements in a fixed predetermined arc to a vertical position at the rear of the ironing stand with the front of the cover forming a substantially horizontal flat surface of substantial width lying below the top level of the ironing elements, and means secured to the cover and to at least one of a pair of said links for counterbalancing the cover during its movement.

40 5. In a combined ironing machine and table, 55 in combination, a supporting structure, ironing means including a heated shoe carried thereby, a cover having a top wall and front, rear and end walls of substantial height, said cover normally resting upon the supporting structure and overlying the ironing elements, a pair of links pivoted to the cover and to the supporting structure, a second pair of links pivoted to the cover and to the supporting structure, and an equalizing rod extending between and operatively connected to the links of one of said pairs for movement therewith for causing said links to move together, said pairs of links cooperating to enable the cover to be moved in a fixed pre-determined path upward and back from its normal position on the supporting structure to a position at the rear thereof.

50 6. In a combined ironing machine and table, in combination, a supporting structure, ironing means including a heated shoe carried thereby, a cover having a top wall and front, rear and end walls of substantial height, said cover normally

resting upon the supporting structure and overlying the ironing elements, a pair of links pivoted to the supporting structure at the upper rear corners thereof and pivoted to the sides of the cover substantially mid-way between the front 5 and rear walls, a second pair of links pivoted to the cover and to the supporting structure, and an equalizing rod extending between and operatively connected to the links of one of said pairs for movement therewith for causing the said links 10 to move together, said pairs of links cooperating to enable the cover to be moved in a fixed pre-determined path upward and back from its normal position on the supporting structure to a position at the rear thereof such that the front 15 wall of the cover lies well below the top level of the ironing elements, whereby little, if any, heat generated by the heated shoe will be directed by said cover toward the operator in front of the machine.

20 7. In an ironing machine, an ironing stand, a cover enclosing the ironing elements, a link pivotally secured to said cover and to said ironing stand, a spring secured to said cover and to said link at a point above the pivot between said link 25 and said cover adapted when the cover is initially raised to lessen the manual effort required therefor and adapted during the subsequent movement of the cover to restrain the movement thereof, and additional link means secured to said cover 30 and to said ironing stand.

8. In an ironing machine, an ironing stand upon which the ironing elements are mounted and upwardly from which they project, a box-like cover adapted to rest upon the ironing stand and 35 enclosing the ironing elements and forming with the ironing stand a table, a pair of links pivotally secured to the ironing stand near its rear portion and pivoted to the cover forwardly of the first-named pivots, a second pair of links pivoted 40 to the cover on an axis at the rear of the pivotal connection of said first-named links to the ironing stand and pivotally connected to the stand on an axis below the first named pivots of said second links and means interposed between the 45 first-named links and cover for counter-balancing the cover as it is moved from a position enclosing the ironing elements to a position at the rear of the ironing stand exposing the ironing elements.

50 9. In an ironing machine, an ironing stand having a horizontal surface supporting ironing elements which project an appreciable distance above the horizontal surface, a box-like cover adapted to rest upon the ironing stand and enclosing the ironing elements and forming with the ironing stand a table, a pair of links pivotally secured to the ironing stand and pivotally secured to the cover forwardly of the first-named pivots and above the level of the horizontal surface, a second pair of links pivoted to the cover on an axis at the rear of the pivotal connection of said first-named links to the ironing stand and pivotally connected to the stand on an axis below the first-named pivots of said second links, 60 and means interposed between one of said pairs of links and the cover for counterbalancing the cover as it is moved from a position enclosing the ironing elements to a position at the rear of the ironing stand exposing the same.

65 10. In an ironing machine, an ironing stand including supporting legs and a fixed substantially horizontal surface supporting ironing elements which project an appreciable distance above the level of the horizontal surface, a hol- 75

low-box-like cover supported by the ironing stand and extending over and enclosing the ironing elements and forming with the ironing stand a table, means secured to the ironing stand and to the cover for enabling the cover to be manually moved in a fixed predetermined arc upwardly and over the ironing elements to a substantially vertical position at the rear of the ironing stand in close proximity thereto with the front of the cover forming a substantially horizontal flat surface of substantial width lying below the top level of the ironing elements.

11. In an ironing machine, an ironing stand, ironing elements thereon, a cover enclosing the ironing elements, a pivot link secured to the ironing stand and to the cover whereby said cover may be manually shifted, spring means secured to said pivot link and to said cover in a manner and position such that said spring is initially contracted and subsequently expanded during the movement of said cover from a position enclosing said ironing elements to a position exposing the same.

12. An ironing machine table comprising a stand and a cover, ironing elements supported on said stand, a pivot link secured to the ironing stand and cover whereby said cover may be manually shifted from a position enclosing the ironing elements to a position uncovering the same, and spring means secured to said pivot link and to said table in a manner and position such that the manual effort required to raise the cover is lessened and the subsequent movement of the cover is counter-balanced.

13. In an ironing machine, an ironing stand having a fixed substantially horizontal surface supporting ironing elements which project an appreciable distance above the horizontal surface, a box-like cover resting in a substantially horizontal position on the ironing stand and enclosing the ironing elements and forming with the ironing stand a table, a pair of links secured to the cover close to the rear lower corners thereof, and secured to the stand close to the rear edge thereof, said links being each of a length substantially half the width of the cover from front to rear, an additional pair of links connected to the stand near the rear thereof adjacent the horizontal surface of the stand and to the cover at points well in advance of the rear edge of the cover for causing the cover to move in a predetermined arc whereby the forward wall of the cover clears the ironing elements and the cover in its open position has the forward side thereof positioned below the upper edge of the ironing elements.

14. In an ironing machine, an ironing stand including a fixed substantially horizontal surface supporting ironing elements which project an appreciable distance above the level of the horizontal surface, a cover enclosing the ironing elements, means comprising a link pivotally secured to said cover and pivotally secured to said ironing stand whereby said cover may be moved from a position enclosing the ironing elements to a position exposing the same, and a spring secured to said cover and to said link for counter-balancing the cover during its movement, said spring in both positions of the cover being substantially entirely within the confines of the cover.

15. The combination of an ironer stand having a table top supporting ironing elements thereon, and a box-like cover member for said ironing elements having a top wall and vertical front, rear and side walls and an open bottom, a pair of links pivotally connected to the rear lower corners

of the cover and to the stand at points an appreciable distance below the top thereof, permitting the cover to have an independent pivotal movement about the connections of said links with the cover and a bodily movement about the lower connections of said links with the stand to a position at the rear of and below the stand, and a second pair of links pivotally connected to the cover and pivotally connected to the stand at a point adjacent the table top and, when the cover is closed, substantially coincident with the axis of connections of the first pair of links with the cover for rotating the cover during its bodily movement to position its front wall in a substantially horizontal plane.

16. In an ironing machine, an ironing stand including supporting legs and a fixed substantially horizontal surface supporting ironing elements which project an appreciable distance above the level of the horizontal surface, a hollow box-like cover supported by the ironing stand and extending over and enclosing the ironing elements and forming with the ironing stand a table, means secured to the ironing stand and to the cover for enabling the cover to be manually moved in a fixed predetermined arc upwardly and over the ironing elements to a substantially vertical position at the rear of the ironing stand and in close proximity thereto with the front of the cover forming a substantially horizontal surface of substantial width lying below the top level of the ironing elements, and means for lessening the manual effort required for raising said cover from its vertical position at the rear of the ironing stand.

17. In an ironing machine, an ironing stand including supporting legs and a fixed substantially horizontal surface supporting ironing elements which project an appreciable distance above the level of the horizontal surface, a hollow box-like cover supported by the ironing stand and extending over and enclosing the ironing elements and forming with the ironing stand a table, means secured to the ironing stand and to the cover for enabling the cover to be manually moved in a fixed predetermined arc upwardly and over the ironing elements to a substantially vertical position at the rear of the ironing stand in close proximity thereto with the front of the cover forming a substantially horizontal flat surface of substantial width lying below the top level of the ironing elements, and means for lessening the manual effort required for raising said cover from each of its limiting positions.

18. An ironing machine cabinet comprising a stand and a cover, ironing elements supported by said stand, means secured to said ironing stand and to said cover for enabling the cover to be manually moved from either an open or a closed position in a fixed predetermined arc over said ironing elements, said cover passing through a neutral or balanced position intermediate the ends of the arc of its travel, and means interposed between said stand and cover for initially assisting in and subsequently restraining the opening movement of said cover.

19. An ironing machine cabinet comprising a stand and a cover, ironing elements supported by said stand, means secured to said ironing stand and to said cover for enabling the cover to be manually moved from either an open or a closed position in a fixed predetermined arc over said ironing elements, said cover passing through a neutral or balanced position intermediate the

ends of the arc of its travel, and means interposed between said stand and cover for initially assisting in both the opening and closing movements of said cover.

- 5 20. An ironing machine cabinet comprising a stand and a cover, ironing elements supported by said stand, means secured to said ironing stand and to said cover for enabling the cover to be manually moved from either an open or a closed 10 position in a fixed predetermined arc over said ironing elements, said cover passing through a neutral or balanced position intermediate the ends of the arc of its travel, and cover counter-balancing means including a spring, interposed 15 between said stand and cover in a manner so that the tension of the spring is progressively decreased and then increased during the movement of the cover from one to the other of its limiting 20 positions.
- 20 21. An ironing machine cabinet comprising a stand and a cover, ironing elements supported by said stand, means secured to said ironing stand and to said cover for enabling the cover to be manually moved from either an open or a closed 25 position in a fixed predetermined arc over said ironing elements, said cover passing through a neutral or balanced position intermediate the ends of the arc of its travel and cover counter-balancing means including a tension spring inter- 30 posed between said stand and cover in a manner so that the tension of the spring works in a direction tending to move the cover from one or the other of its limiting positions, there being a neutral point intermediate the ends of the arc of travel of the cover where the tension of the spring 35 has no tendency to move the cover.

22. In a combined ironing machine and table, in combination, a supporting structure, ironing means including a heated shoe carried thereby, 40 a cover having a top wall and front, rear and end walls of substantial height, said cover normally resting upon the supporting structure and overlying the ironing elements, a pair of links pivoted to the supporting structure at the rear upper 45 corners thereof and pivoted to the sides of the cover substantially midway between the front and rear walls, a second pair of links pivoted to the cover and to the supporting structure, said pairs of links cooperating to enable the cover to be 50 moved in a fixed predetermined path upward and back from its normal position on the supporting structure to a position at the rear thereof such that the front wall of the cover lies well below the top level of the ironing elements, whereby 55 little, if any, heat generated by the heated shoe will be directed by said cover toward the operator in front of the machine.

23. In an ironing machine, an ironing stand supporting ironing elements which project an appropriate distance above the level of the stand, 60 a hollow box-like cover supported by the ironing stand and extending over and enclosing the ironing elements and forming with the ironing stand a table, means secured to the ironing stand and to the cover for enabling the cover to be manually moved in a fixed predetermined arc upwardly and over the ironing elements to a substantially vertical position at the rear of the ironing stand in close proximity thereto with the 65 front of the cover forming a substantially hori- 70

zontal flat surface of substantial width lying below the top level of the ironing elements.

24. In a combined ironing machine and table, in combination, a supporting structure, ironing means including a heated shoe carried thereby, 5 a cover having a top wall and front, rear and end walls of substantial height, said cover normally resting upon the supporting structure and overlying the ironing elements, a pair of links pivoted to the cover and to the supporting structure 10 and enabling the cover to be moved upward and back from its normal position on the supporting structure to a position at the rear thereof such that the front wall of the cover occupies a substantially horizontal position well below the 15 top level of the ironing elements, whereby little, if any, heat generated by the heated shoe will be directed by said cover toward the operator in front of the machine, and means operatively connected to the cover and to the supporting structure 20 for causing the cover during said movement to move in a fixed pre-determined path.

25. In a combined ironing machine and table, in combination, a supporting structure, ironing means including a heated shoe carried thereby, 25 a cover having a top wall and front, rear and end walls of substantial height, said cover normally resting upon the supporting structure and overlying the ironing elements, a pair of links pivoted to the cover and to the supporting structure, a 30 second pair of links pivoted to the cover and to the supporting structure, said pairs of links cooperating to enable the cover to be moved in a fixed predetermined path upward and back from its normal position on the supporting structure 35 to a position at the rear thereof such that the front wall of the cover lies well below the top level of the ironing elements, whereby little, if any, heat generated by the heated shoe will be directed 40 by said cover toward the operator in front of the machine.

26. In an ironing machine, an ironing stand having a fixed substantially horizontal surface supporting ironing elements which project an appreciable distance above the level of the horizontal surface, a hollow box-like cover supported by the ironing stand and extending over and enclosing the ironing elements and forming with the ironing stand a table, a pair of links pivotally secured to the ironing stand at substantially the 45 level of the horizontal surface and pivotally secured to the cover forwardly of said pivots and above the level of the horizontal surface, a second pair of links pivotally secured to the cover close to the rear lower corners thereof and pivotally secured to the ironing stand below the level 50 of the ironing elements close to the rear edge of the stand but forwardly of the pivotal connection of the second pair of links to the cover, said links being proportioned and arranged whereby the 55 cover may be manually swung in a fixed predetermined arc upwardly and over the ironing elements to the rear of the ironing stand, the pivotal connection between the second pair of links and cover when the latter is in fully opened position being located rearwardly of the pivotal connections between both pairs of links and the stand to facilitate upward swinging movement of the 60 cover to its closed position.
